SUPERHEATER FOR HIGH TEMPERATURE STEAM

Wilbur H. Armacost, New York, N. Y., assignor to The Superheater Company, New York, N. Y.

Application March 9, 1933, Serial No. 660,108

5 Claims. (Cl. 122—476)

My invention relates to superheaters and particularly to those designed to produce steam of high temperature.

In order that my invention, together with the objects and advantages thereof, may be clearly and readily understood, I will now describe in detail and in connection with the accompanying drawing a superheater installation selected by way of example from a number of possible embodiments of my invention. In the drawing,

Fig. 1 is a sectional elevation of a superheater boiler having a superheater in accordance with my invention.

Fig. 2 is a fragmentary detail on an enlarged scale of a superheater similar to that shown in Fig. 1 but including certain modifications.

Fig. 3 is a fragmentary detail of a portion of a superheater similar to Fig. 1 but embodying other modifications.

Fig. 4 is a fragmentary sectional view illustrating still further modifications.

A number of superheater installations have been proposed in which the pressure and the final steam temperature are quite high compared to the average of past practice. In such installations, it has usually been assumed to be necessary to employ special material for the superheater units to prevent undue rate of deterioration of such units from the high temperature gases and steam. It has been found, however, that superheaters employing such special material for the units are subject to undue leakage at the joints between the units and headers, particularly the high temperature header, unless such headers or header, are, or is, also made of the same material as the units. I have conceived that such difficulty of high leakage is due to the different coefficient of thermal expansion of the material used for the units as compared to the coefficient of expansion of the material used for the header, such difference in the coefficients being important because the units are sometimes subjected to sudden changes in temperature of considerable amount due to changes in load and in firing conditions. I have conceived further that such difficulty may be avoided in two ways.

One such way is by forming the units with end portions to be joined to the high temperature header and of the same ordinary material as such header. Such end portions should, of course, lie outside of the path of the heating gases and this is ordinarily readily arranged. In case such end portions are apt to be damaged by the steam, they may be given a thin protec-

tive coating of aluminum alloy, or other substance, adapted to protect them from the steam without changing their thermal coefficient of expansion. The other such way is by making the units of special material throughout and using seat portions in the header of material having the same coefficient as that of the units.

In the drawing, I have illustrated a boiler 10 of ordinary type having a gas pass 12 therein in which is a superheater composed of a plurality of units, one of which appears at 14. The units 14 extend in parallel between a header 16 for the saturated steam and a header 18 for the superheated steam. It is assumed that the installation of which boiler 10 is a part employs 10 gases for heating the units 14 and a final steam temperature such that special material must be used for the portions of the units in contact with such gases. The arrangement illustrated is one well adapted to such an assumption in that the 20 steam flow is entirely counter-flow to that of the heating gases, a condition well-known to produce the maximum metal temperature for a given final steam temperature and initial temperature of the heating gases. In the arrangement shown in Fig. 1, it is assumed that the 25 high temperature ends of the units 14 are connected to header 18 by ordinary rolled joints. As usual, the header 18 is placed outside the path of the heating gases. The ends of units 14 30 pass outside the contour of the boiler 10 to make connection with the header 18 so that the end portions of the units are also out of contact with the heating gases. I take advantage of this fact to make an end portion 20 on each of the units 35 14 of the same material as the header 18, both such header and such portions being of the relatively cheap carbon steel while the main body portions of units 14 are of alloy steel or other material well adapted to withstand high temperatures even if in contact with gas and steam also at high temperature. The material of the header 18 and that of the end portions 20 being, however, of substantially the same composition and therefore substantially the same thermal coefficient of expansion, the joints 22 between the header and the end portions have no unusual tendency to leak steam. The end portions 20 can be readily united with the main 40 portions of the units 14 by welding as indicated 45 at 24.

Preferably also the inlet ends of the units 14 have portions 26 thereon of ordinary low carbon steel like that employed for saturated header 16, the portions 26 being united with the main por- 55

tions of the units 14 by weld joints 28. However, the need for special end portions is greater at the high temperature ends of the units 14 than at the low temperature ends of such units so that I do not limit myself to the use of special end portions 26.

In Fig. 2, the units 14a are seen to be similar to units 14 except that they are joined to the header 18a for superheated steam by a known type of releasable joint 22a instead of by the rolled joint shown in Fig. 1.

Fig. 3 shows a portion of a unit 14b and a header for superheated steam 18b united by an ordinary rolled joint 22, the unit 14b, however, entering the header 18b on the side instead of at the top and the header 18b having normally closed openings 30 therein to facilitate the rolling of the joints 32. Openings 30 must of course be closed during periods when the apparatus is in use by known or other suitable means and I have illustrated a plate such as 32 for this purpose.

It will be evident that much the same effect as in Fig. 1 can be obtained by providing seats of alloy steel in a carbon steel header and making the end portions of the units also of alloy steel of substantially the same coefficient of expansion as the seat portions of the header, whether or not the major portions of the units have said coefficient. Such an arrangement is illustrated in Fig. 4 and is the reverse in certain respects of that of Fig. 1. In Fig. 4, the header 18c is of carbon steel but has apertured alloy steel inserts 30 shrunk therein to act as seats for the joints 22c. In Fig. 4, however, the elements 14c are of alloy steel throughout so that they have no permanent joints 24 and the releasable joints 22c are formed by contacting surfaces of substantially the same thermal coefficients of expansion. I do not limit myself to shrinking in the inserts 30, but may thread them into the header 18c, or weld them into such header, or both thread and weld them in place in such header, certain known forms of screw threaded joints, as well as shrunk and welded joints being adapted to be made up so tight as to be free of the danger of leaking and therefore to make the seat pieces 30 permanent parts of the header.

While I have shown my invention in connection with a boiler, it will be understood that my invention

may be used in separately fired superheaters.

What I claim is:

1. A superheater having a header for superheated steam having a certain thermal coefficient of expansion, superheater units connected to deliver steam to such header and having substantial heat absorbing portions of metal having a thermal coefficient of expansion different from that of said header but having end portions integral therewith and contacting with said header, said end portions having a thermal coefficient of expansion substantially the same as that of the portions of said header with which they contact.

2. The combination of a carbon steel header, units joined thereto and having substantially heat absorbing portions of high temperature alloy steel, but having ends integral therewith of carbon steel for joining to and contacting with said header.

3. The combination of a header whose major portion is of carbon steel, and heater units arranged to deliver fluid thereto, said units having heat absorbing portions material sections of which are of alloy steel, and said header and units having joints therebetween intended to be broken when a unit is removed from said header, the parts in contact in said joints having substantially the same coefficients of expansion and permanently fixed to the header and to the units.

4. A superheater having a header for superheated steam having a certain thermal coefficient of expansion, superheater units connected to deliver steam to such header and having substantial heat absorbing portions of metal having a thermal coefficient of expansion different from that of the major portion of said header but having end portions integral with said units and contacting with metal portions joined to said header in such manner that the joints between said metal portions and said header remain tight against pressure upon removal of the units, the contacting parts of said units and header having substantially the same coefficient of expansion.

5. In a heater the combination of a header and a pipe to be connected thereto, the two parts being of metals having different coefficients of expansion; and a metallic piece permanently secured to one of said parts and releasably engaging the other and having substantially the same coefficient of expansion as the latter.

WILBUR H. ARMACOST.
